UNITED STATES PATENT OFFICE

FRANK BERENSTEIN, OF CHELSEA, MASSACHUSETTS, ASSIGNOR TO PANCO RUBBER COMPANY, OF CHELSEA, MASSACHUSETTS, A CORPORATION OF MASSACHUSETTS

METHOD OF MAKING RUBBER HEELS

Application filed February 6, 1931. Serial No. 513,841.

The present invention relates to a method of producing rubber heels, and more particularly to such a method designed primarily for the production of rubber heels with embedded 5 plugs employed for ornamental or non-slipping purposes.

The purpose of the invention is to produce heels of this character by a new and improved method which insures the proper location and conformation of the individual 10 plugs, and at the same time unites the plugs firmly in the body of the finished heel.

To the accomplishment of this purpose I propose to employ a heel mold which may be 15 made in three parts as is usual, and provided with mold pins for receiving and locating the plugs and accompanying washers.

In producing the heel one or more plugs severed or cut from a length of tubing of 20 proper dimensions is placed upon a mold pin and surmounted by a cupped washer of somewhat larger diameter than the plug. After the requisite number of plugs and washers have been assembled, a blank of uncured rubber 25 composition is placed thereover, and the mold assembled and the contents subjected to temperature and pressure. In the process of vulcanizing, the rubber of the blank is caused to flow about the plugs and washers. The 30 material of the plug, which is also uncured rubber, preferably with a friction material combined therewith, is prevented from substantial deformation by the conjoint action of the cupped washer at one end of the plug, 35 and the reception of the opposite end of the plug in a positioning recess in the mold. The washer and recess combine to prevent splaying out or gross deformation of the uncured plug during the vulcanizing pressure, at the 40 same time permitting the rubber of the heel blank to flow therearound and to be effectually bonded to the plug and accompanying washer. The mold pins are ordinarily provided with washer-receiving shoulders for positioning the washer within the finished heel, as is 45 customary.

In the actual construction of the heel it is proposed to provide friction plugs about a portion of the nail-receiving recesses, the remaining being supplied merely with washers

in the usual manner. As indicated, the recesses having no plugs may be provided with ornamental projections similar in appearance to the projecting portion of the plug.

In the accompanying drawing illustrating 55 the best method of practicing the invention, Fig. 1 is a plan view of the mold plate containing the washer-locating pins and determining the configuration of the tread face of the heel; Fig. 2 is a section through a mold 60 cavity, illustrating the placing of the plugs and washers thereon and the location of the heel blank before pressure is applied; Fig. 3 is a section of the same cavity after the molding operation has been completed, with 65 the heel contained therein; Fig. 4 is a plan view of the finished heel; and Fig. 5 is a detail showing one of the plugs ready for application to a mold pin.

In carrying out the present process, as 70 shown in the illustrated embodiment of the invention, the plugs 10, preferably cut from a length of tubing, are dropped over all or a portion of the mold pins 12, centering in the concave recesses 14 formed at the base of the 75 mold pins in the bottom 16 of the mold cavity. The configuration of these recesses 14 determines the appearance and conformation of the plugs in the finished heel. Superimposed over each plug is a concave washer 18, 80 slightly larger than the plug and adapted when pressure is applied to the mold to seat upon a shoulder 20 formed on the mold pin. In this position of the washer it will be evident that the plug is engaged at opposite 85 ends by the washer and recess 14, and that due to the proximity of the washer and recess, the plug is substantially encompassed thereby and is actually held against any major distortion due to the pressures employed in the 90 vulcanizing operation. In other words, the assembly serves to retain the form of the plugs in their general dimensions, and prevents flowing of the plugs into the body of the heel during vulcanization. It does not, 95 however, prevent or interfere with the flowing of the heel body therearound, and the proper bonding of the heel body to the embedded washer and plug.

As shown in the illustrated embodiment of 100

the invention, only certain of the mold pins are provided with friction plugs. The remaining pins are provided with nail-receiving washers, which may be and preferably are 5 of smaller size than the washers which surround the friction plugs. These washers are indicated at 22.

After the completion of the article, as shown particularly in Fig. 3, the heel is provided with a series of embedded washers, and with one or more embedded friction plugs which, during the vulcanizing operation, are bonded and united with the surrounding heel body. These plugs may preferably have 15 combined with the rubber composition a certain amount of fibrous material for increasing the frictional qualities, and in the illustrated embodiment of the invention are preferably compounded of a different color from 20 the major portion of the heel body. The plugs are inserted in the molds in an unvulcanized state, together with the heel blank, so that the single operation completely bonds and vulcanizes both the body and embedded 25 plugs at one and the same time. At its completion the finished heel has the general surface appearance indicated at 25 in Fig. 4. This heel has a series of nail-receiving recesses 30 extending completely about the periphery, certain of these recesses being provided and surrounded with embedded friction plugs. The remaining recesses are merely provided with washers, but may have embossed protuberances at the tread surface 35 to improve the appearance of the heel, and cause these recesses to conform in general appearance with the tread portion of the plugs.

What is claimed is:

1. The method of making rubber heels provided with inserted plugs which consists in assembling one or more unvulcanized rubber tubes of generally cylindrical form over shouldered positioning pins in the plate of a mold cavity provided with a forming recess 40 at the base of each pin of greater diameter than the diameter of the rubber tube, superimposing over each tube and supported thereby a concave washer of larger diameter than that of the tube, assembling an unvulcanized rubber heel blank above the pins, and subjecting the entire assembly to heat and pressure for the purpose of simultaneously forcing the heel blank over the pins, washers and tubes and the washers on to the shouldered portions 45 of the pins, with the tubes forced downwardly into the recesses and conforming therewith while held against further deformation at opposite ends by the washers and recesses respectively.
2. The method of making rubber heels provided with inserted plugs which consists in assembling one or more unvulcanized rubber tubes of generally cylindrical form over shouldered positioning pins in the plate of a mold cavity provided with a surrounding 50

concave forming recess at the base of each pin of greater diameter than the diameter of the rubber tube, superimposing over each tube and supported thereby a concave washer of larger diameter than that of the tube, assembling an unvulcanized rubber heel blank above the pins, and subjecting the entire assembly to heat and pressure for the purpose of simultaneously forcing the heel blank over the pins, washers and tubes and the washers on to the shouldered portions 55 of the pins, with the tubes forced downwardly into the concave recesses and conforming therewith while held against further deformation at opposite ends by the washers and recesses respectively.

In testimony whereof I have signed my name to this specification.

FRANK BERENSTEIN.
